UNITED STATES PATENT OFFICE.

BOYD L. MCKNIGHT, OF WASHINGTON, DISTRICT OF COLUMBIA, ASSIGNOR OF ONE-HALF TO JOSEPH E. UEBEL, OF WASHINGTON, DISTRICT OF COLUMBIA.

NECKTIE-PRESSING DEVICE.

1,352,294.

Specification of Letters Patent. Patented Sept. 7, 1920.

Application filed September 26, 1919. Serial No. 326,510.

To all whom it may concern:

Be it known that I, BOYD L. MCKNIGHT, a citizen of the United States, residing at Washington, in the District of Columbia, have invented new and useful Improvements in Necktie-Pressing Devices, of which the following is a specification.

The object of my present sole invention is the provision of a simple, inexpensive and neatly-appearing device in the form of a wardrobe appurtenance, and constructed and arranged in such manner that neckties may be expeditiously and easily pressed in a thorough manner without the employment of skilled labor, and without the aid of heat.

To the attainment of the foregoing the invention consists in the improvement as hereinafter described and definitely claimed.

20 In the accompanying drawings, hereby made a part hereof:

Figure 1 is a side elevation of the pressing device constituting the best practical embodiment of my invention that I have as yet devised.

Fig. 2 is an elevation of one edge of the device.

Fig. 3 is an elevation of the other edge of the device.

30 Fig. 4 is a transverse section taken in the plane indicated by the line 4—4 of Fig. 1 and the dampening pad in proper working position relatively to an interposed necktie.

35 Fig. 5 is a longitudinal section in the plane indicated by the line 5—5 of Fig. 1, illustrating the same arrangement.

Similar numerals of reference designate corresponding parts in all of the views of the drawings.

Among other elements my novel device comprises two thin and flat layers 1, of wood, card-board, fiber or other material compatible with the purpose of the device. 45 The said layers 1 are adapted to be used in opposed and parallel relation, and adjacent to one end they are provided with pairs of registered apertures 2 through which are threaded loops 3, preferably of silken cord. 50 The said loops 3 permanently connect the layers 1 together, so that there is no liability of either being misplaced or disassociated

from the other, and they also constitute a convenient "hanger up" through the medium of which the device may be conveniently suspended on a dresser or in a wardrobe.

One of the layers 1 is provided on its outer side and adjacent to one end with a keeper loop 4, of wire or other suitable material, and adjacent to its other end the said layer is provided with two clamps 5. The said loop 4 and clamps 5 have to do with the blotting pad 6 and the dampening pad or strip 7, when said pads or strips are not in use, the pads or strips being at that time held in the loop 4 and under the clamps 5, so as to contribute to the facility with which the device may be handled as a unit. It will of course be understood that when the device is to be put into use, the pads 6 and 7 will be removed from the loop 4 and clamps 5; also that subsequently to the pressing of a tie, the pads will be restored to the position shown in Fig. 1, relatively to the layer carrying the loop 4 and the clamps 5.

On one of its longitudinal edges, and adjacent to one of its ends, one of the layers 1 is provided with a cleat 8, and on the opposite longitudinal edge and adjacent to the opposite end of the device, the other layer 1 is equipped with a similar cleat. These cleats 8 are each for the connection of a complementary binding cord 9 which, after being tightly wound about the opposed layers, is designed to have its free end secured temporarily in or by its respective cleat. It will of course be understood in this connection that cord-securing appurtenances other than cleats, may be employed on the layers 1.

My novel necktie pressing device is designed more particularly for pressing and prolonging the usefulness of four-in-hand scarfs, and in a practical use of the device and after the cords 9 are unwound and one of the layers 1 is swung from over the other, the blotting pad 6 is neatly positioned within the folds of the large end portion of the tie, and the dampening pad or strip 7, after being impregnated with water, is superimposed upon the said comparatively large end portion of the tie. The layers 1 are then brought into opposed relation, and

the cords 9 are tightly wound about the layers and the free ends of the cord are temporarily secured in the manner stated, when after a short period, the said large portion of the scarf-like tie will be found to be pressed in a thorough and finished manner.

I would also have it understood that my novel press may be used to advantage for the purpose of preserving fine ties in a neat and uncrushed state.

The use of my novel device is not restricted to the pressing of one tie at a time. On the other hand, a plurality of superimposed ties may be pressed in concert; one of the pads 6 and one of the pads or strips 7 being employed in conjunction with each tie under pressure.

When more than one pad 6 and pad or strip 7 are provided as appurtenances to the press, all of the said pads or strips when not in use will be retained in the loop 4 and under the clamps 5.

Manifestly when not in use the device may be suspended from a dresser, without detracting in any measure from the neat appearance thereof.

Having described my invention, what I

claim and desire to secure by Letters-Patent, is:—

1. A necktie press comprising two flat layers of rigid material loosely and permanently connected together at one end so that one may be swung from over the other, fastening devices carried by and exterior of the layers adjacent to opposite ends thereof and binding cords, one complementary to each fastening device and connected at one end thereto and adapted to be wound about the layers and detachably fastened at its opposite end to the fastening device.

2. A necktie press comprising two flat layers of rigid material permanently connected together adjacent to one end of the device and so that one layer may be swung from over the other; one of the said layers being provided on its outer side and adjacent to one end with a keeper loop designed to retain one end of a pad or pads and being also provided adjacent to its opposite end with clamping means to detachably hold the other end of the pad or pads.

In testimony whereof I affix my signature.

BOYD L. McKNIGHT.
